PORTABLE HAND LANTERN

Alfred L. Mell and Charles S. Packer, Chicago, Ill., assignors to Justrite Manufacturing Company, Chicago, Ill., a corporation of Illinois

Application April 2, 1954, Serial No. 29,828

Term of patent 3½ years

(Cl. D48—24)

Fig. 1

Fig. 2

Fig. 3

To all whom it may concern:

Be it known that we, Alfred L. Mell and Charles S. Packer, both citizens of the United States, residing at Chicago, county of Cook, and State of Illinois, have invented a new, original, and ornamental Design for Portable Hand Lantern, of which the following is a specification, reference being had to the accompanying drawing, forming a part thereof.

We claim:

The ornamental design for a portable hand lantern, as shown.
